UNITED STATES PATENT OFFICE.

WILLIAM E. PRINDLE, OF MANITOWOC, WISCONSIN.

ROTARY DRIER.

1,098,402.

Specification of Letters Patent. Patented June 2, 1914.

Application filed April 23, 1913. Serial No. 763,085.

To all whom it may concern:

Be it known that I, WILLIAM E. PRINDLE, a citizen of the United States, and residing at Manitowoc, in the county of Manitowoc and State of Wisconsin, have invented certain new and useful Improvements in Rotary Driers, of which the following is a specification, reference being had to the drawings annexed hereto.

10 My invention relates generally to driers, and more specifically to the class of inclined rotary driers having an internal cylindrical hot air flue provided therein for the purpose of drying wet material fed into the drier.

15 One of the principal objects of this invention is the provision of an improved drier wherein high temperatures are effectively employed at the point where, ordinarily, the material is at its coldest and 20 wettest stage; and which is furthermore designed to obtain the application of graduated lower temperatures to the material as it correspondingly parts with its moisture in its progression to the rear or discharge 25 end. Another object of my invention is a novel and effective arrangement of drier parts at the feed end, purposed to relieve the restricted condition ordinarily found at this end of the drier, with a view to afford a larger open space at this point to obtain a more uniform action of the usual induction means. A further object is the provision of novel means adapted to regulate the flow and distribution of heated air from 30 the hot air cylinder; and a still further object is to provide an effective high-duty drier wherein the heat units are economically and effectively applied to the material 35 to the utmost advantage.

40 These, together with such other objects as may hereinafter appear, or are incident to my invention, I attain by means of a construction illustrated in preferred form in the accompanying drawings, wherein:—

45 Figure 1 is a longitudinal sectional view of a drier embodying my invention.

Figure 2 is a transverse section through the front end of a drier in Figure 1.

Figure 3 is an enlarged detailed drawing 50 of a portion of the flue in Figure 1; and

Figure 4 is a cross-section of Figure 3 along the line III—III.

In describing my invention, the letter A indicates the outer cylindrical shell preferably lying at an angle to the horizontal, and C used to rotate in the usual manner by

suitable gearing B, and mounted on bases 6 having rollers 7 in supporting engagement with tires 8 formed on the shell.

C represents the furnace chamber which is shown positioned under the shell A, having its walls continued upwardly to surround the forward portion 9 of the shell and spaced away therefrom, to form an enclosed hot air chamber D, which is provided 60 for the purpose of receiving the heated air and gases passing upwardly through the checkered arch 10 from the furnace.

Positioned about the upper portion of the hot air chamber D to form a supplementary air chamber E is an exterior covering 11, provided with an air inlet opening 12 and an outlet opening 13, which latter communicates with the furnace chamber through a depending connecting pipe F, 75 having its lower end bifurcated to provide the two off-set extremities 14 and 15 extending laterally through a side wall of the furnace chamber, the former terminating immediately under the furnace grate and the 80 other at a point transversely intermediate the bridge wall 16 and rear wall 17.

The air in the supplementary chamber E which becomes heated by the high temperatures existing in the adjacent chamber D, 85 has an induced flow from the chamber E to the furnace chamber C through the suction blower f interposed in the pipe connections. This induced flow is controlled by a damper g mounted in each of the offset extremities 14 and 15, affording a convenient means for regulating the furnace draft, and also for moderating at will the degree of heat within the chamber D. Should the necessity 90 arise for a rapid cooling down of the drier, 95 a cold air inlet h is provided in the walls of the chamber D for that purpose.

The numeral 18 indicates a suction fan communicating with the front end of the drier through a stationary vapor bonnet 19, 100 about which the said front end rotates. Carried by the bonnet and projecting into the drier is a feed spout 20 to feed the wet material into the drier shell.

Extending longitudinally through and 105 suspended centrally of the drier shell A for rotary movement therewith is an inner hot air cylinder or flue H, preferably formed in the two sections 21 and 22. The rear section 22 as shown is of smaller diameter than 110 the front section 21, and the sections are coupled together at their inner proximate

ends by clamping elements passing through a series of spaced separators 22 thus providing the outlets 23. The latter are protected against the intrusion of material there- 5 through into the flue, by the provision of a rearwardly extending guard 24, one end of which is fastened securely about the section 21 (preferably by the clamping elements above referred to), and its flared rear end 10 may be braced by similar separating members 25 interposed and secured between it and the periphery of the smaller section 22.

The walls of that portion of the rear flue section within the guard 24 are perforated 15 to provide a series of protected ports 26 through which additional hot air may be drawn into the drier shell by the suction fan. To regulate the passage of hot air through these ports, I provide a sleeve 27 capable of 20 limited endwise movement on the cylinder to open the said ports which normally are closed by the sleeve, the latter on being moved to any predetermined position may be locked by a cylinder bolt and nut, the 25 sleeve being slotted at 27° to receive the bolt and to permit this movement.

Inclosing the rear end of the shell is a hood 28 having internal lifting arms 29 which, as the drier revolves, carries the 30 dried material into a cone discharge 30 leading into the discharge outlet 31, formed in the rear face of the hood 28. The rear end of the flue H terminates short of the hood 28 and has a flared rear outlet governed by an 35 air valve 32 which has reciprocative movement to open and close the outlet through a suitably supported rod 33 which extends through the hood for its convenient operation.

40 From an inspection of Figures 1 and 2, it will be seen that the front portion of the drier shell is completely inclosed and has axial movement within the hot air chamber D, which latter as previously stated is positioned directly above the furnace chamber C to receive the heated gases therefrom, and to all substantial effect forms an integral portion thereof.

This arrangement provides for the direct 50 application of the highest temperatures to the wet and cold material as it is fed into the drier shell through the feed spout, but in order that the material in its progression rearwardly toward the discharge end be 55 further subjected to heat and thereby evaporate retained moisture, I provide a row of aligned and intervalled openings indicated at 34 and 35 in the walls of that portion of the drier shell A within the hot air chamber and 60 in the walls of the forward end of the flue H respectively. These openings are connected by the radial conduits 36 flanged for purposes of attachment to the walls of the respective cylinders. It will be here noted 65 that the front end of the flue H is closed,

and terminates at a point removed from, or short of, the feed end of the drier shell. The flue being thus closed at its front end, then with the exhaust fan in operation, the hot gases in the chamber D have an induced 70 flow past the conduits, through the flue H and thence through the flue outlets as desired.

In the practice of my invention, I have found it preferable to employ an auxiliary 75 row of conduits as at 36^a differing only from the others in that they have play room in the eccentric or slotted openings 35^a to allow for expansion and contraction of the flue, the inner annular flange in this case not 80 being fastened to the flue, but nevertheless providing a tight joint between the conduits and contiguous portions of the flue wall. Expansion and contraction of the inner cylindrical flue is also taken care of through 85 the spiders 37 in which the flue is suspended for slight longitudinal movement, the only rigid connection between the shells preferably being at the interposed flanged conduits 36, as set forth.

90 In the form of construction shown, the operation of the drier is substantially as follows:—The wet and cold material fed in a mass into the drier shell at the feed or front end comes into contact with a large 95 area of heating surface afforded by that portion of the shell within the hot air chamber and the front end of the flue H, whereby it is subjected to exceedingly high temperatures to heat the mass and evaporate a large 100 percentage of the moisture therein contained.

As the drier revolves the material is cascaded by the series of lifting blades 38 and 105 39, and in its progression rearwardly to the discharge end constantly parts with its moisture as it comes into contact with the heat radiating from the inner flue, until it reaches the discharge end as a uniformly dried product. Correspondingly, the heated air and gases in the flue suffer a gradual 110 reduction in temperature and velocity when passing rearwardly, so that the dry and light material at the rear end is not scorched or disturbed.

Furthermore, the arrangement of the 115 drier front end is such that a large area of open space is afforded at this point, permitting uniform action of the suction fan which effectually exhausts the heavy moisture at that end, but does not draw out light particles where the temperature is low, as the velocity correspondingly diminishes. This situation is aided by the provision of the intermediate outlets 23, through which air and gases of a now reduced temperature 120 pass. This flow is accelerated by closing the air valve 32 and further increased by opening the ports 26, or may be decreased at this point by closing the ports and opening the valve, whereby a lesser or greater 125 130

proportion of the heated air may be drawn to the discharge end of the drier, diminishing or increasing the temperature as may be desired.

5 Another feature of my invention is the provision of the supplementary chamber E which not only retards atmospheric radiation of heat from the hot air chamber but utilizes heat ordinarily lost, which flows 10 through the connections to the furnace under complete control, the damper *g* in the pipe sections being opened or closed to accelerate or reduce the draft in the furnace as the case may be, or to increase or diminish to 15 some extent the temperature in the chamber D.

The entire operation is continuous and under complete control. The essential features, elements and the operation of the machine, together with its simplicity and other advantages thereof, will be readily apparent to those skilled in the art.

Having thus described my invention and illustrated its use, what I claim as new and 20 desire to secure by Letters Patent, is the following:—

1. The combination in a rotary drier, of an outer shell provided with a feed opening, an inner flue mounted therein for conducting heated air rearwardly through the shell, a hot air supply chamber communicating with the said inner flue and providing a means for externally heating the feed end portion of said shell, and means for inducing a flow of heated air through the said inner flue to other portions of the shell.

2. In a rotary drier, the combination of an outer cylinder having a feed member, a hot air chamber forming an extension of a furnace chamber and surrounding the feed end portion of the outer cylinder, an inner hot air cylinder receiving its source of heat from one of the said chambers, and exhaust means at the feed end of the outer cylinder adapted to induce a flow of heated air rearwardly through the inner cylinder to the uninclosed portion of the outer shell.

3. In a drier, an outer shell, an inner hot air flue mounted therein adapted to conduct heated air rearwardly and having a closed front end, and a hot air chamber communicating radially with the said inner flue, substantially as and for the purpose set forth.

4. In a drier, a hot air chamber, a drier shell having a portion of its length received within the said chamber for the external application of heat thereto, and means for internally conducting heated air through the other portion of the drier shell consisting of an inner flue suspended within the drier shell.

5. In a machine of the class described for drying wet material, the combination of a drier shell provided to receive therein the material to be dried, a furnace chamber hav-

ing its walls continued upwardly to form a hot air chamber, the said drier shell having a portion of its length received within the hot air chamber for the direct application of external heat to the wet material, and 70 conducting means within the drier adapted to receive a supply of heat from the said hot air chamber, whereby the material in its progression to the other portion of the drier shell is deprived of any retained moisture. 75

6. In combination, an outer drier shell, a hot air conductor mounted therein and comprising two sections disposed in telescopic relation thereby providing an outlet to the 80 outer shell, one of the sections being provided with supplementary outlet openings formed in its walls, and controlling means for the supplementary outlet openings, substantially as described.

7. In combination in a drier, a furnace chamber C, a drying cylinder A, an outer chamber E having an outlet in its walls, an intermediate hot air chamber D adapted to receive hot air or gases from the said furnace chamber for application to the said cylinder and said chamber E, and a connection between the said outlet and the furnace chamber, substantially as described.

8. In combination, an exhaust member, a cylindrical drier shell communicating at its front end with the exhaust member, a hot air supply chamber D inclosing the said shell adjacent the front end, a hot air conductor lying within the drier shell and communicating with the hot air supply chamber through one or more lateral conduits, the front end of the conductor being closed and terminating at a point short of the drier front end, all so arranged to obtain a uniform flow of heated air through the conductor on actuation of the exhaust member.

9. In a rotary drier, an outer shell, a hot air conductor lying within the outer shell and provided with an intermediate air outlet, said conductor communicating at one end with a source of heat and having an outlet opening at its other end, and valvular means to close the said outlet opening whereby the heated air then flows through the intermediate outlet, thereby decreasing the temperature of that portion of the drier contiguous to the said outlet opening.

10. In a rotary drier, exhaust means, an outer drying shell communicating at its feed end with said exhaust means, means to externally heat that portion of the drying shell which first receives the cold and wet material comprising an inclosing hot air chamber, means for conducting heat to other portions of the drying shell consisting of a cylindrical member having one or more radial conduits opening in the walls of the outer shell, and provided with an outlet opening.

11. In combination, an outer drier shell,

a hot air conductor mounted therein and consisting of telescoping sections, said conductor being provided with an outlet communicating with the outer shell, a supplementary outlet formed in the wall of one of the sections, and a hood mounted on the conductor adapted to guard both of the said outlets, substantially as described.

12. In combination, an outer drier shell, a flue suspended therein provided with an outlet communicating with the outer shell and a supplementary outlet, a rearwardly extending guard about the said outlets, and controlling means for the supplementary outlet consisting of a sleeve disposed within the guard and movable on the said flue.

13. In combination, a hot air chamber D, an outer chamber E above the chamber D, a drying cylinder A and an inner cylinder H adapted to receive heat from the hot air chamber D, and a conduit F having its inlet opening in the chamber E and depending therefrom to communicate with the chamber D, substantially as described.

14. In combination, exhaust means, a drier shell, an external heating chamber surrounding the front end of the drier shell, and a conductor cylinder disposed within the drier shell and adapted to communicate with the said external heating chamber.

15. In combination, an outer drier shell, an external heating chamber surrounding the front end of the outer shell, a conductor cylinder disposed within the drier shell and adapted to communicate at its front end with the said external heating chamber, and

valvular means within the open rear end of the cylinder, substantially as described.

16. In combination, a feed member, an exhaust member, a drier shell A communicating at its front end with said feed and exhaust members, an external heating chamber D about said front end, an inner conductor cylinder H having its front end in proximity to said feed and exhaust members and adapted to receive a supply of heated air from the chamber D.

17. The combination in a rotary drier, of a shell adapted to contain the material to be dried, means for applying the heat externally to the front end of the shell, and means communicating with the last mentioned means for internally applying the heat to the material as it progresses rearwardly to the discharge end of the shell, substantially as described.

18. In combination, exhaust means, a drier shell, a conductor cylinder disposed within the drier shell and having its front end closed, an external heating chamber extending about the front end of the drier shell and adapted to communicate with the said conductor cylinder, substantially as described.

In testimony whereof I have hereunto signed my name in the presence of the two subscribed witnesses.

WILLIAM E. PRINDLE.
